CLEANING COMPOSITION AND METHOD OF
CLEANING INTERNAL COMBUSTION EN-
GINESWilliam J. Sweeney and Joshua A. Tilton, Baton
Rouge, La., assignors to Standard-I. G. Com-
pany, a corporation of DelawareNo Drawing. Application November 20, 1934
Serial No. 753,898

2 Claims. (Cl. 87—5)

This invention relates to cleaning compositions or compounds and more particularly to a cleaning composition or compound for removing deleterious bodies that are formed in internal combustion engines.

5 In the normal course of internal combustion engine operation it is well known and recognized that some ingredients of the crankcase lubricant combine with oxygen to form resinous or asphaltic material commonly called "sludge." This sludge, either alone or as a water emulsion, tends to adhere to the motor parts and is in some ways detrimental to smooth engine performance. In some instances, emulsified sludge has been known 10 to completely stop the flow of oil through engine oiling systems, resulting in a rise in bearing temperatures, high enough to melt the bearing metal.

15 To remove sludge, the engine has to be dismantled and cleaned, or washed with some suitable solvent oil. In the latter course, the solvent usually consists of ordinary petroleum fractions or the more aromatic coal tar naphthas, either alone or in mixtures of light lubricating oil.

An object of this invention is to provide an improved cleaning composition for substantially 20 dissolving the resinous and asphaltic material formed by the combination of oxygen with some ingredients of a lubricating oil while being used in an internal combustion engine.

25 This and other objects and advantages will be obvious from the following description.

The general method used in cleaning internal combustion engines is to drain the used oil out of the crankcase, preferably while the engine is 30 hot, add the solvent oil, run the engine for several minutes and drain. This procedure usually must be repeated several times if it is desired to have the draining come out clear. The crankcase is then refilled with clean lubricating oil.

35 According to this invention, destructively hydrogenated solvent naphthas of the type usually designated "hydroformed" naphthas are found to be decidedly effective solvents for resinous or asphaltic materials formed in crankcases of internal combustion engines, and in this respect provide an improved cleaner over the usual run of solvents such as common petroleum type solvents and coal tar solvents such as benzol and toluol. The manufacture of these solvents is according to a known process, but it may be gen-

erally stated that a gas oil or kerosene, preferably a heavily cracked fraction or a solvent extract from a low grade kerosene or gas oil by treatment with selective solvents, such as liquid sulfur dioxide, phenol, nitrobenzene, alcohols, ketones, furfural, etc., is subjected to the action of hydrogen gas at a temperature above 900° F. in vapor phase and with a total hydrogen and oil partial pressure in excess of 30 atmospheres and usually around 200 atmospheres. It is important that a catalyst insensitive to sulfur be used in the hydrogenation reaction. Among these, the oxides and sulphides of metals of the VI group of the periodic table are of particular importance, and especially mixtures thereof with oxides of the metals of the III and IV groups, and with zinc oxide, magnesia and the like. The rate of flow may be from 1.5 to 4 volumes of oil per hour per volume of catalyst and the amount of hydrogen is ordinarily from 1000 to 4000 cu. ft. per barrel of oil. The physical properties of hydroformed solvents may be illustrated as follows:

Fraction No.	Boiling range ° F.	Gravity A. P. I.	Kauri butanol value	Flash point ° F.
1.....	275 to 365.....	34.0	75.6	61
2.....	365 to 419.....	26.2	77.3	135
3.....	419 to 460.....	19.6	85.7	190

30 Hereafter in the specification and claims the hydroformed solvent naphthas will be known as "hydrosolvents." The hydrosolvents having a boiling range of 419° F. to 460° F. have been found to be better solvents for the resinous and asphaltic bodies found in internal combustion engines. The hydrosolvent fractions may be used as such or in a mixture consisting of the hydrosolvent fraction and other solvent oil, such as a mineral, animal or vegetable oil, preferably a higher boiling lubricating oil.

35 The inherent property of hydrosolvents, especially the 419° to 460° F. fraction, that makes them especially adapted for removing sludge formed in internal combustion engines may be known from the following illustration:

40 Sludge, formed by the combination of oxygen with some ingredients of a lubricating oil, was separated from the lubricating oil by settling and

decantation. The action of various solvents on this separated sludge was determined and the following results were obtained:

5	Solvent	Percent of lubricating oil sludge soluble in solvent
10	Kahlbaum benzine (122° F. to 266° F. boiling range). Cleaners naphtha (300° F. to 410° F. boiling range). Benzol.....	0.0 2.3 18.3
	Toluol.....	17.9
	Hydrosolvent (365° F. to 419° F. boiling range).....	19.5
	Hydrosolvent (419° F. to 460° F. boiling range).....	50.5

- 15 Here the hydrosolvent was prepared by hydro-forming a sulfur dioxide extract from a low grade burning oil, and it will be noted that the 419° to 460° F. fraction is at least 2½ times more effective as a solvent than the other compositions
20 with which it was compared.

The foregoing description is merely illustrative

and various changes and alternative arrangements may be made within the scope of the appended claims in which it is our intention to claim all inherent novelty in the invention as broadly as the prior art permits.

We claim:

1. A cleaning composition as cleaning agent for crankcases of internal combustion engines containing a destructively hydrogenated solvent mineral oil having a boiling range of 419° to 460° 10 F. and a kauri butanol value of about 85.7.

2. A method of cleaning crankcases of internal combustion engines which comprises draining the used oil out of the crankcase, adding a cleaning composition containing a destructively hydrogenated solvent mineral oil having a boiling range of 419° to 460° F. and a kauri butanol value of about 85.7 and a mineral lubricating oil, running the engine for several minutes and draining. 15
